UNITED STATES PATENT OFFICE.

DANIEL H. SNYDER, OF SNYDERVILLE, OHIO.

RAILROAD-CROSSTIE.

1,360,594.

Specification of Letters Patent. Patented Nov. 30, 1920.

Application filed September 10, 1919. Serial No. 322,855.

To all whom it may concern:

Be it known that I, DANIEL H. SNYDER, a citizen of the United States, residing at Snyderville, in the county of Clark and State of Ohio, have invented certain new and useful Improvements in Railroad-Crossties, of which the following is a specification, reference being had therein to the accompanying drawing.

10 This invention relates to railroad cross ties, and has for its particular object to provide a combination cross tie, part metal and part wood, which will have the cushioning qualities of wood ties and the durability and 15 general wearing qualities of metal ties.

It is an object of my invention to provide a tie of the two materials that will be of simple, substantial construction, requiring only a minimum of wood to provide for the 20 wood cushioning effect, and which will be standardized with respect to the bolts and nuts which are used to secure the several parts together.

It is a further object of my invention to 25 provide the tie with suitable rail clamps of improved construction which act to brace the steel rails laid upon the ties both laterally and longitudinally and also to prevent rising or torsional movement of the rails relative to the ties.

It is also a feature of the invention to provide the metal portion of the tie, on portions thereof which contact with the soil or other material of which the road bed is constructed, 35 with lugs or cleats, preferably made integrally with the metal portion of the tie, and acting to anchor the tie in the material of the road bed to prevent movement of the tie relative to the steel rails or the road bed 40 itself.

In the accompanying drawings,

Figure 1 is a plan view of my improved tie with the steel rails secured thereto;

Fig. 2 is a side elevation of the construction shown in Fig. 1;

Fig. 3 is an end view of the same;

Fig. 4 is a bottom plan view of the metal portion of the tie; and

Fig. 5 is a detail of one of the rail clamps.

50 As here shown the metal portion of the tie consists of a channel 1 preferably of wrought iron or steel. Fitted into each end of the channel is a short section of wood, being in the form of a rectangular-shaped 55 wood block, having its upper surface substantially flush with the upper edges of

the channel, its outer end flush with the end of the channel, and its inner end extending substantially beyond the plane of the steel rail. The wood blocks may be secured in 60 the channels in any suitable manner, as here shown, by lag screws 5.

The ties are laid in the road bed in the usual manner of embedding a portion of the tie in the road bed, the material of which 65 the road bed is usually constructed, such as gravel, crushed stone, slag, cinders, etc., being tamped about the tie to level the tracks laid upon the ties and, as far as possible, to prevent or minimize movement of the ties 70 relative to the road bed.

To further minimize movement of the ties relative to the road bed my improved tie is provided on the under side thereof with downwardly projecting cleats or lugs 6 75 which, as here shown, are formed integrally with the metal channels by punching V-shaped holes 7 through the bottom of the channel, the metal being cut free on two sides of the aperture and remaining intact 80 on the other side, thus forming the triangular-shaped cleat 6 which projects downwardly a considerable distance substantially at right angles to the plane of the tie and serves therefore to more securely anchor the 85 tie in the road bed. To make the cleats more effective they are preferably staggered and arranged alternately in planes substantially at right angles to each other.

The apertures 7 serve the further useful 90 purpose of drain outlets for the metal channel, thus preventing or minimizing any accumulation of water in the channel and tending, therefore, to prevent rotting of the wood blocks 2.

When the ties have been thus arranged in the road bed the steel rails 3 are laid thereon and are secured to the ties by means of opposite clamps 4—4, secured to the metal portion of the tie by bolts 8, the clamps having 100 jaws 4^a by means of which they are adjusted to the rail flange 3^a, the end of the jaw being in the form of a nose 4^b which abuts against the web 3^b of the rail, the opposite clamps thus acting one against the other to prevent 105 lateral movement of the rail.

Inwardly adjacent each set of clamps, directly beneath the rail and extending beyond the rail flange to clear the opposite edges thereof, are depressions 9, formed in 110 the opposite sides of the metal channels, which serve as clearance spaces for the rail

flange, thereby permitting the steel rails to rest wholly upon the wood blocks 2, the slight flexibility of the wood acting to give to the rail mountings the resilient or cushioning effect essential to good track construction. To this end also the clamp jaws are made to contact with the upper portions of the rail flanges only, there being ample clearance space provided in the clamp to 10 avoid contact with the rail flange on the under side thereof.

It will be noted that the jaws of the rail clamps conform to the angle of the rail flange and that a relatively wide holding surface is thus provided which acts effectively to prevent any twisting or torsional movement of the rails, as well as acting together with the portion of the jaw 4^b to prevent longitudinal and lateral movement 20 of the rails relative to the ties.

As here shown, the bolt heads and nuts employed in the assembling of my improved ties and securing the steel rails thereto are all of uniform standard size so that one 25 wrench or track tool will fit any bolt head or nut, this provision being made in the interest of standardized construction.

While my invention is simple in construction the novel features thereof are relatively of great importance. The construction is cheap but substantial, and results in track construction which in all respects is dependable, being free from certain common defects which it is desirable to overcome.

While all the good qualities of wood ties are preserved in effect in my improved tie only the minimum of wood is required which, in view of the increasing scarcity of 40 wood suitable for ties, is of first importance. Furthermore the wood blocks as used in the ties are protected largely from deterioration in the metal channels which are properly drained through the apertures 7 to 45 minimize the accumulation of moisture therein, thus acting as a further protection to the wood. Also, as will be noted, no spikes are used to secure the rails to the wood so that all exposed surfaces of 50 the wood are kept intact and are not subject therefore to the destruction common to wood ties into which rail spikes are driven.

As in the case of my earlier invention relating to improved railroad ties, which 55 forms the subject matter of Patent No. 1,233,413, issued July 17, 1917, the wood block feature of the present invention provides for interchangeability of the faces of the block relative to the steel rails and also 60 longitudinal adjustment relative thereto. Thus by removing the lag screws which secure the blocks to the metal channels the blocks may be removed and reversed and shifted longitudinally in either direction 65 without disturbing the metal tie. By this

arrangement practically the entire surface of the blocks may be utilized by adjusting the blocks relative to the rails from time to time as depressions are formed therein from the wear of the rails.

70

Having thus fully described my invention, what I claim as new and desire to secure by Letters Patent, is:—

1. A railroad cross tie comprising a metal channel, clearance spaces for the rail flange 75 in the sides, downwardly projecting cleats struck from the bottom of the channel arranged alternately in planes substantially at right angles to each other to anchor the tie to the roadbed, a wooden block secured 80 in the metal channel, the exposed face of which is substantially flush with the edges of the channel and a steel rail resting wholly and directly upon the surface of said block.

2. A railroad cross tie comprising a metal channel, clearance spaces for the rail flange 85 in the sides, downwardly projecting V-shaped cleats struck from the bottom of the channel arranged in planes substantially at right angles to each other to anchor the tie 90 to the roadbed, a wooden block secured in the metal channel, the exposed face of which is substantially flush with the edges of the channel and a steel rail resting wholly and directly upon the surface of said block.

95

3. A railroad cross tie comprising a metal channel, clearance spaces for the rail flange in the sides, downwardly projecting V-shaped cleats struck from the bottom of the channel, such cleats being staggered and 100 arranged in planes at right angles to each other to anchor the tie to the roadbed, a wooden block secured to the channel, the exposed face of which is substantially flush with the edges of the channel and a steel rail 105 resting wholly and directly upon the surface of said block.

4. A railroad cross tie comprising a metal channel, clearance spaces for the rail flange in the sides, a plurality of downwardly projecting V-shaped staggered cleats formed on the bottom of the channel to anchor the tie to the roadbed and a drain aperture formed adjacent to each cleat.

5. A railroad cross tie comprising a metal 115 channel, clearance spaces for the rail flange in the sides, downwardly projecting cleats struck from the bottom of the channel arranged alternately in planes substantially at right angles to each other to anchor the tie to the roadbed, a wooden block secured in the metal channel the exposed face being substantially flush with the edges of the channel, a steel rail resting wholly and directly upon the surface of said block and secured 120 to said channel by oppositely disposed clamps contacting with the web and opposite flanges of the rail.

In testimony whereof I affix my signature.
DANIEL H. SNYDER.
